Primary Examiner — Susan E Krakower

Assistant Examiner — Jerry Shiuan-Hua Hsu

(57) **CLAIM**

We claim the ornamental design for a vehicle hail guard, as shown and described.

DESCRIPTION

FIG. 1 is a front view of a vehicle hail guard, showing our new design;

FIG. 2 is a rear view of the claimed design.

FIG. 3 is a top view of the claimed design.

FIG. 4 is a side view of the claimed design; and,

FIG. 5 is a perspective view of the claimed design.

1 Claim, 4 Drawing Sheets
